UNITED STATES PATENT OFFICE.

GIULIO MARCHETTI, OF HALIFAX, COUNTY OF YORK, ENGLAND, ASSIGNOR
TO JOHN CROSSLEY & SONS, OF NEW YORK, N. Y., AND LONDON, ENGLAND.

DESIGN FOR A RUG.

SPECIFICATION forming part of Design No. 19,333, dated October 1, 1889.

Application filed September 2, 1889. Serial No. 322,792. Term of patent 3½ years.

To all whom it may concern:

Be it known that I, GIULIO MARCHETTI, of Halifax, county of York, England, have invented a certain new and original Design for 5 Rugs; and I do hereby declare the following to be a full, clear, and exact description of the same, such as will enable others skilled in the art to which it appertains to make and use the design, reference being had to the accompanying drawing, which forms part of this specification.

My invention relates to a design for rugs; and it consists in a novel ornamentation of the filling or body design of the rug and border surrounding the same, substantially as hereinafter described, and pointed out in the 15 claim.

The accompanying drawing is a plan view of a rug embodying my design. 20 The letter A marks the leading feature or center of the rug, which center consists of a group of conventional flowers, leaves, and stems, the main stem growing from a ground-

work effect representing conventional waves or water B. Two corner-pieces C C, forming 25 characteristic panels representing conventional water, are placed at the head of the main group or feature of the rug. The inner band D of the border of same rug represents lace or ribbon work, while the outer band E 30 of same border is a combination of conventionally-treated water grasses and blossoms, the whole of said border being in strict harmony with the main or central group A.

Having thus described my invention, I 35 claim—

A design for a rug, consisting of a group of conventional flowers, leaves, and stems surrounded by a border composed of design representing ribbon or lace effect with conventionally-treated water grasses and blossoms, 40 substantially as shown and described.

GIULIO MARCHETTI.
